UNITED STATES PATENT OFFICE

95,687

DESIGN FOR A HEATING STOVE

Martin L. Hunker, Dover, Ohio, assignor to The
Reeves Manufacturing Company, Dover, Ohio,
a corporation of Ohio

Application September 6, 1934, Serial No. 53,211

Term of patent 14 years

To all whom it may concern:

Be it known that I, Martin L. Hunker, a citizen of the United States, residing at Dover, in the county of Tuscarawas and State of Ohio, have invented a new, original, and ornamental Design for Heating Stoves, of which the following is a specification, reference being had to the accompanying drawing, forming part thereof.

The figure is a perspective view of a heating stove, showing my new design.

The dominant and characteristic feature of the design is the shape of the top of the stove which is downwardly curved at its edge and then formed into a channel at the point where it connects to the side walls of the stove.

I claim:

The ornamental design for a heating stove, as shown and described.

MARTIN L. HUNKER.
